United States Patent Office.

JOHN W. TULL AND GEORGE STEVENSON, OF ZIONSVILLE, INDIANA.

Letters Patent No. 82,662, dated September 29, 1868.

IMPROVED BOOT AND SHOE-HEELS.

The Schedule referred to in these Letters Patent and making part of the same.

TO ALL WHOM IT MAY CONCERN:

Be it known that we, JOHN W. TULL and GEORGE STEVENSON, of Zionsville, in the county of Boone, and State of Indiana, have invented certain new and useful Improvements in Boot and Shoe-Heels; and we do hereby declare that the following is a full, clear, and exact description thereof, reference being had to the accompanying drawings, and to the letters of reference marked thereon, which form a part of this specification, and in which—

Figure 1 represents a section,

Figure 2 a plan, and

Figure 3 a side view of our rubber boot or shoe-heel.

The novelty of this invention consists in the peculiar manner of securing an India-rubber heel to boots or shoes, substantially as hereinafter set forth.

To enable others skilled in the art to which our invention appertains to make and use the same, we will now proceed to describe its construction and operation.

In the accompanying drawings—

A represents an India-rubber heel, which is made concave on its upper side.

B represents a leather or metal plate, which is made in the shape of the heel, but a little larger than the upper part, thus forming a flange, C, around the heel when secured to the plate B. The object of this flange or projection is to enable the heel to be finally secured to the boot or shoe by means of pegs or thread.

The plate B is cut out in the centre, in the shape of the heel, and perforated with holes between the inner and outer edges, as represented in fig. 2, and is then pressed in a concave shape, as represented in fig. 3.

The concave part of the heel A being heated to a melted state, you press the plate B in the melted gum, which causes the gum to pass through the perforations made in the plate B, running together as it passes through, and forming a thickness on the upper side of the plate B sufficient to secure the plate to the heel.

Having thus fully described our invention, what we claim, and desire to secure by Letters Patent, is—

The employment of an India-rubber heel for boots or shoes, when used in combination with a leather or metal plate, the said heel and plate being secured together substantially in the manner herein described.

In testimony that we claim the foregoing as our own, we affix our signatures in presence of two witnesses.

JOHN W. TULL.

GEORGE STEVENSON.
